TUB SUPPORTING AND LEVELING DEVICE

Victor E. Schmiedeknecht, Louisville, Ky., assignor to Standard Sanitary Manufacturing Company, a corporation of New Jersey

Application February 12, 1936, Serial No. 63,560

8 Claims. (Cl. 4—173)

My present invention relates to a supporting and leveling device for bathtubs and the like and more particularly to a device which enables bathtubs to be supported and leveled during installation and adjustments made from above the tub rim.

I am aware that it has hitherto been proposed to provide adjustable brackets for the same general purpose herein specified. Prior proposals have taken a number of forms, some of which are more or less satisfactory and some of which are relatively unsatisfactory. In some instances the proposed arrangement has been flimsy and too difficult of access, thereby requiring not only highly skilled labor, but also consuming too much time and too many adjustments before the final setting is secured. In practically all instances adjustments must be made below the tub rim level and this not only made adjustment difficult but frequently resulted in inaccurate adjustment. While this particular trouble has been overcome in one instance of which I am aware, this particular instance does not provide a practical arrangement. In the first place, it depends upon a movable lever fulcrumed at its center, and in the second place, it tends to place destructive strains on the tub rim. Then again, the shortness of the lever arm makes adjustment difficult and there is a tendency toward distortion and jamming. A study of the situation has therefore convinced me that while the problem has been, in a measure, solved, it has not been correctly and permanently solved.

It is accordingly one of the objects of my invention to produce a tub leveling and supporting device which not only overcomes the defects and disadvantages of prior known devices, but which has new and useful features peculiar to its own construction.

Another object of my invention resides in the provision of a casting which receives a tub supporting element in such manner that necessary or desired adjustments can be simply, quickly, and conveniently made from above the tub rim level.

Another object of my invention resides in the provision of a simple casting having a tubular portion provided with a longitudinal slot and a bolt movable within said tubular portion and having an angular portion extending through the slot for tub supporting and leveling purposes, together with means for making and maintaining adjustments.

Other and further objects and advantages will be clearly apparent from the following description

or will be understood by those skilled in this art.

In the accompanying drawings:

Figure 1 is a plan view illustrating a tub supported by a number of devices in accordance with the present invention;

Fig. 2 is a side elevational view of Fig. 1;

Fig. 3 is an enlarged elevational view of the device of my present invention with portions broken away for clarity;

Fig. 4 is an edge elevational view looking from left to right of Fig. 3;

Fig. 5 is a sectional view on line V—V of Fig. 3; and

Fig. 6 is a perspective view of the invention as used.

Similar numerals indicate corresponding parts throughout the various views.

Referring to the drawings, the numeral 10 indicates a suitable tub or like plumbing fixture which may be made of any suitable material or combination of materials, such as now customarily employed. The rim of this tub is indicated by the numeral 11, and the configuration of the rim is clearly apparent from Fig. 6. In conventional manner the tub is provided on its under surface 25 with the supporting projections 12 and the tub is, of course, provided with the usual drain outlet designated by the numeral 13.

Numerals 14 represent the wooden studding forming a part of the usual wall construction of 30 a bathroom and it is to these studs that my present device is secured. However, I wish to point out that while the studding is preferably so used, as shown, and while the supporting device is preferably adapted to be secured thereto, I am not 35 limited in this respect because I have found that the supporting devices can also be set into the hollow tile which is frequently used for wall construction, or the devices can be set into concrete where such is used for the wall construction. 40 Therefore, the term "studding" as hereinafter used is to be understood as including hollow tile or concrete wall construction as well as the wooden studs illustrated.

As will be apparent from Figs. 1 and 2 especially, 45 I utilize a plurality of supporting devices which are adapted to be secured to the studding of the wall construction. Six such supporting devices, designated as a whole by the numeral 15, are illustrated in Figs. 1 and 2, but the precise number 50 thereof is variable according to size and space factors and in accordance with the requirements of any particular installation. In each case, the supporting devices are so located and distributed as best to effect the purpose and intent of the 55

invention and so as to give full and accurate control over the precise positioning of the tub or other plumbing fixture. The details of the present invention will be clearly apparent from Figs. 5 to 6, inclusive, which will now be described in detail.

Each of the supporting devices consists of a suitable casting which has the general configuration shown. This casting, for example, comprises 10 a flat plate-like portion 16 terminating top and bottom in a horizontally extending flange 17. A suitable number of apertured bosses or the like 18 are provided for the reception of wood screws or other securing devices and it is evident that the 15 casting is adapted to be secured to the studding 14 in this manner. The forward portion of the casting, that is, the portion contiguous to the tub 10, consists of a tubular portion 19. Extending from the bottom of this tubular portion up to 20 a desired height thereof, but terminating short of the top, is a slot 20 extending longitudinally of the tubular portion 19. The tubular portion is flat on the tub side so that it lies flush with the studding and enables close juxtaposition of tub 25 rim, studding, and support.

In the tubular portion 19 and movable longitudinally thereof is a supporting member such as the bolt 21. This bolt 21 is threaded at its upper end and is provided with a straight portion 22 and an angular portion 23. This angular portion extends through the slot 20 to receive and support the tub rim as clearly shown in Fig. 6. The angle of the angular portion is so correlated with the curvature of the under side of the tub rim 30 that the two are substantially complementary and there is thus provided a strong support which does not induce any unnecessary or undesirable strains into the tub rim. The upper end of the bolt 21 is provided with an adjusting nut 24 and 35 a lock nut 25 which is superposed on the adjusting nut. It is clearly apparent that both of these nuts are above the level of the tub rim and therefore adjustments can be made above the tub rim in simple and convenient manner. To make a 40 change in the height of the tub rim adjacent any of the supporting devices, I merely need to loosen lock nut 25 and then move adjusting nut 24 either to the left or to the right the desired number of turns or partial turns. This turning of nut 24 results either in raising or lowering the angular portion 23 of the bolt 21, and when the desired 45 position is reached, the lock nut is tightened to preserve the adjustment. The upward movement of angular portion 23 is limited by shoulder 26.

50 In installing bathtubs, particularly built-in tubs, it is necessary to support them during installation. It is also necessary to ensure their being level. This work is usually done by a plumbing contractor. The tubs are usually installed before the floor and wall tile are laid. It therefore becomes essential to prevent damage occurring after laying the floor and wall tile. Where improper support is furnished the tub breaks away from the wall leaving a gap between 55 tub and wall into which water and dirt may enter and thus increasing damage. This ordinarily occurs from settling of the tub due to shrinkage of the studding, etc., and further may result in the tub becoming out of level.

60 My present invention prevents such and moreover enables shrinkage, etc., to be compensated. By installing a number of devices in accordance with the present invention perfect positioning of the tub is possible during installation very simply

and economically with minimum labor and all adjustments can be conveniently made from above the tub rim level.

What I claim as new and desire to secure by Letters Patent is:

1. A tub support comprising a casting adapted to be secured to a bathroom wall construction, said casting being provided with a tubular portion having a longitudinal slot, a supporting member in said tubular portion having an angular portion extending through said slot for supporting a tub rim, means for raising and lowering the said angular portion and means for maintaining the desired positioning of the supporting member. 10

2. A tub supporting and leveling device comprising a casting, a tubular portion unitary with said casting and having a longitudinal slot, a supporting member in said tubular portion having an angular portion extending through said slot for receiving the rim of a tub, the upper end of 15 the supporting member being threaded and extending beyond the tubular portion of the casting and adjusting and lock nuts on the threaded end of said supporting member. 20

3. A tub supporting and leveling device comprising a casting, a tubular portion on said casting, a bolt in said tubular portion capable of positioning movement therein, said bolt having a projecting tub rim supporting portion and means for securing the bolt in desired position in the tubular 30 portion. 35

4. A tub supporting and leveling device comprising a casting adapted to be secured to a wall construction, a slotted bolt-receiving portion on said casting, a bolt therein having an angular portion projecting through the slot for supporting a tub rim, and adjusting and lock nuts on said bolt. 45

5. In a tub supporting and leveling device, a casting adapted to be secured to a stud or the like, the casting having a unitary tubular portion 40 provided with a longitudinal slot.

6. In a tub supporting and leveling device, a casting adapted to be secured to a stud or the like, the casting having a unitary tubular portion 45 provided with a longitudinal slot extending from the bottom of the tubular portion to a point short of the top thereof, thereby providing a slot delimiting shoulder, the unslotted part of the tubular portion having a flat face. 50

7. In combination with a tub, a tub-rim supporting member, a unitary casting provided with a portion for receiving and holding said supporting member so as to allow for movement of said member in said portion and for locking it in desired position, the whole being characterized by the fact that the supporting member can be moved and locked from above the level of the tub rim and by the fact that the casting can be secured to any convenient portion of a bathroom wall 60 construction, such as the studding thereof. 55

8. A tub supporting and leveling device comprising a plate-like metal member adapted to be secured to the studding of a bath room wall construction, a slotted tubular portion constituting 65 a part of said plate-like metal member, a supporting member movable up and down in said tubular portion and having a tub receiving projection extending through said slot, means for effecting up and down movement of the supporting member and means for maintaining the desired positioning thereof. 70
